SEPARATION OF NAPHTHENES FROM HYDROCARBON MIXTURES USING 7 A. TO 12 A. MOLECULAR SIEVES
Raymond N. Fleck, Albany, and Carlyle G. Wight, Fullerton, Calif., assignors to Union Oil Company of California, Los Angeles, Calif., a corporation of California
No Drawing. Filed Apr. 5, 1963, Ser. No. 270,806
20 Claims. (Cl. 208—310)

This invention relates to the separation of hydrocarbon mixtures and in particular concerns an improved process for separating naphthenic hydrocarbons from non-naphthenic hydrocarbons.

In the refining of petroleum by modern techniques, complex hydrocarbon mixtures of the gasoline boiling range are frequently produced which comprise paraffin and naphthene hydrocarbons. The latter have appreciably higher octane numbers than paraffins of the same boiling range, and are hence particularly desirable for use as blending stocks for motor fuels. Certain naphthenes, particularly cyclohexane, are also of great value in the production of a variety of organic chemicals. At the present time, however, conventional methods for separating naphthenes from complex hydrocarbon mixtures are either economically impractical or are effective only with particular mixtures.

It is accordingly an object of this invention to provide an improved process for separating naphthenic hydrocarbons from complex hydrocarbon mixtures.

A further object is to provide a process for separating naphthenes from non-naphthenic hydrocarbons of substantially the same boiling point.

Another object is to provide a process for improving the anti-knock rating of hydrocarbon mixtures which comprise naphthenic and non-naphthenic hydrocarbons of the gasoline boiling range.

Other and related objects will be apparent from the following detailed description of the invention, and various advantages not specifically referred to herein will be apparent to those skilled in the art upon employment of the invention in practice.

We have now found that the foregoing objects and their attendant advantages can be realized in an adsorptive separation process in which a complex hydrocarbon feed mixture comprising naphthenic hydrocarbons is contacted with a molecular sieve type adsorbent. More particularly, we have found that naphthenic hydrocarbons can be separated from paraffins as well as aromatic hydrocarbons by a process which comprises: (1) contacting a fluid hydrocarbon mixture with a lean molecular sieve adsorbent to obtain a rich adsorbent containing a large proportion of the non-naphthenic components of the feed mixture and a non-adsorbed phase enriched in the naphthene components, (2) separating the rich adsorbent from the non-adsorbed phase, and (3) treating the rich adsorbent to desorb the non-naphthenic hydrocarbons therefrom and return the adsorbent to a lean state for re-use in the next succeeding cycle of operation.

Considering now the process of the invention in further detail, it is generally applicable in the vapor phase to complex hydrocarbon mixtures of the gasoline boiling range comprising naphthenic hydrocarbons containing 5 or 6 carbon atoms, e.g., cyclopentane, cyclohexane, and methyl cyclopentane. The lowest boiling paraffin in the hydrocarbon feed mixture should boil no more than about 20° F. below the boiling point of the naphthene compo-

2

nent for the vapor phase embodiment of the invention to be effective, and preferably the paraffin component has a boiling point less than about 15° F. below the naphthene component being separated. The liquid phase embodiment of the process of our invention is generally applicable to hydrocarbon mixtures of the gasoline boiling range comprising naphthenic and non-naphthenic hydrocarbons, i.e., to mixture boiling over the range between about 100° F. and about 400° F. and comprising naphthenic and non-naphthenic components ranging in molecular weight from about C₅ to about C₁₂. Preferably, the liquid phase feed mixture has a wide boiling range of at least about 100° F. and typically has an initial boiling point of about 100° F. and a final boiling point of about 400° F. or higher, e.g., a full range aviation gasoline. Usually, of course, such hydrocarbon mixtures are of petroleum origin, but they may also be derived from coal tar, tar sand, oil shale, or other sources. Typical feed mixtures to the process include fractions from straight-run gasolines, thermally and catalytically cracked gasolines, reformates, isomerizates, etc. In general, the straight-run and cracked feeds will comprise substantially only naphthenic and paraffinic hydrocarbons, and the separation effected is one of separating naphthenes from paraffins. Reformates, on the other hand, comprise appreciable amounts of aromatic hydrocarbons. One of the features of the present process lies in its ability to separate naphthenes from both paraffins and aromatics. A particular advantage of the process of our invention is that the liquid phase separation of naphthenes is effectively accomplished on gasoline fractions of very wide boiling range, i.e., having a boiling range from about 100° F. to about 400° F. or higher. A further advantage is found in the fact that complete separation is attained regardless of the relative proportions of naphthenic and non-naphthenic hydrocarbons in the feed mixture. Either the more readily adsorbed non-naphthenic hydrocarbons or the less readily adsorbed naphthenic hydrocarbons can be the major component of the feed mixture with equally effective separation being accomplished.

The adsorbent employed in the present process is a molecular sieve, preferably having a pore size between about 7 A. and about 12 A., such as is described in British Patent No. 777,233. As a class, molecular sieve adsorbents are crystalline partially dehydrated zeolitic metallo alumino silicates having pores of substantially uniform diameter which can vary from as little as 3 A. to 15 A. or greater, depending upon the identity and proportion of the component elements. Of these materials there are two principal commercial types, the so-called "Type A" and "Type X," which differ in their X-ray diffraction patterns, apparent densities, and other characteristics. Both types have been used to separate substances of different molecular size and shape, and it is generally considered that the adsorptive selectivity of molecular sieves is due to their containing uniform pores whose diameter is of molecular magnitude. Thus, the ability of a molecular sieve whose pore diameter is about 5 A. to separate straight-chain paraffins from branch-chain paraffins is considered to be due to the fact that the maximum molecular dimension of the straight-chain paraffins is somewhat less than 5 A., whereas that of the branched-chain paraffins is somewhat greater than 5 A. Consequently, the smaller straight-chain molecules can enter and be held in the pores of the 5 A. sieve, whereas the branched-chain molecules are too large to enter pores

of such small size. In the present process, however, the adsorbent cannot operate in such manner since the pore size is greater than the minimum molecular dimension of any of the paraffinic, naphthenic, or aromatic hydrocarbons present in the feed stream. On the other hand, it does not operate as a conventional adsorbent or even as would be expected from the teachings of the aforesaid British Patent No. 777,233. The latter clearly teaches that the Type X molecular sieves preferentially adsorb polar, polarizable, and unsaturated molecules and reject non-polar and saturated molecules. From such teaching it would be expected that aromatics would be adsorbed in preference to naphthenes and paraffins and that naphthenes would be adsorbed in preference to paraffins. As is hereinafter shown, however, we have found that in the present process, both paraffins and aromatics are adsorbed in preference to the naphthenes.

As stated, the adsorbents which are employed in accordance with the invention are zeolitic partially dehydrated metallo alumino silicates having pores of a substantially uniform diameter between about 7 Å. and about 12 Å. Certain naturally occurring minerals can be heated to dehydrate the molecule and obtain an activated zeolitic adsorbent of such type. However, we greatly prefer the synthetic materials which are conveniently prepared by heating suitable quantities of alumina and silica with an excess of sodium hydroxide and thereafter washing out the excess caustic to obtain a Type X zeolitic sodium alumino silicate having the approximate molecular structure $[6\text{Na}_2\text{O} \cdot 6\text{Al}_2\text{O}_3 \cdot 15\text{SiO}_2]$ on a water-free basis, and having a uniform pore diameter of about 13 Å. The uniform pore diameter of this product can be altered by exchanging part of the sodium cation with other metals. For example, such product can be treated with a concentrated solution of a calcium salt, e.g., calcium chloride, at superatmospheric pressure and at 20°-175° C., washed with water to remove excess calcium chloride, and thereafter partially dehydrated by heating to obtain a Type X calcium sodium alumino silicate having a pore diameter of about 10 Å. and having an average molecular structure on a water-free basis corresponding to

Other divalent cations such as magnesium, strontium, barium, beryllium, zinc, cobalt, nickel, and the like can be employed instead of calcium. Other monovalent metals such as potassium, silver, cesium, etc., may be used instead of sodium. Further details regarding the properties and preparation of Type X molecular sieves are to be found in British Patent No. 777,233. While any molecular sieve having a pore diameter between about 7 Å. and about 12 Å. can be employed in accordance with the preferred embodiment of the invention, it is further preferred to use a 10 Å. pore size calcium sodium alumino silicate such as referred to above. This particular product is available commercially from Linde Company, Tonawanda, New York, under the trade name "Molecular Sieves 10X." The sodium salt described above is also available from the same company, under the trade name "Molecular Sieves 13X." These commercial materials can contain substantial amounts of inert binder materials.

The optimum particle size of the adsorbent will depend upon the manner in which it is used in the process, i.e., as a fixed compact bed, a fluidized bed, etc., but is usually between about 2 and about 400 mesh, preferably between about 4 and about 30 mesh for fixed and moving compact beds and between about 100 and about 300 mesh for fluidized beds.

The adsorbent is preferably employed in the form of a dense compact fixed or moving bed which is alternately contacted with the feed and then desorbed. In the simplest embodiment of the invention, the adsorbent is employed in the form of a single static bed, in which case the process is only semi-continuous. Preferably, a set of two or more static beds is employed in fixed-bed contact-

ing with appropriate valving so that the feed stream is passed through one or more adsorbent beds while the desorption is carried out in one or more of the other beds in the set. The direction of flow during adsorption and desorption can be either up or down through the adsorbent, but preferably the adsorption is carried out in one flow direction and the desorption in the other. Any of the conventional apparatus employed in static bed fluid-solids contacting can be used. A moving compact bed of adsorbent has a much greater separation efficiency than a fixed compact bed of the same size because of the ability of the former to provide reflux. The moving compact bed is therefore preferable when an extremely high degree of separation is desired or when the feed mixture separation factor is poor.

In one embodiment of the invention the hydrocarbon feed mixture is contacted with the adsorbent in the vapor phase. Thus, the temperature is at least as high as the dew point of the feed mixture at the particular pressure employed. The pressure is usually near atmospheric but can be either subatmospheric or superatmospheric. In general the adsorption is carried out at a temperature between about 0° F. and about 800° F., preferably between about 100° F. and about 650° F., and usually at pressures between about atmospheric and about 1,000 p.s.i.g., preferably between about 0 p.s.i.g. and 200 p.s.i.g. The immediate products of the initial adsorption step are: (1) a non-adsorbed vapor phase which is rich in the naphthenic components of the feed mixture and lean in paraffins and aromatics, and (2) a solid rich adsorbent containing adsorbed paraffins and aromatics and lean in naphthenes. The solid and vapor phases are separated, and the latter is passed to storage as the purified naphthene product of the process. The rich adsorbent, on the other hand, is treated to desorb the hydrocarbons therefrom and to return it to a lean state for reuse. According to one mode of operation, such treatment merely comprises subjecting the rich adsorbent to an elevated temperature and/or a reduced pressure, i.e., when the initial adsorption step is carried out at, say, 300° F. and 75 p.s.i.g., the adsorbed component can be effectively recovered by heating the rich adsorbent to, say 650° F. and/or reducing the pressure to 0 p.s.i.g. or less. The use of elevated temperature can also be combined with the use of a stripping gas in the known manner.

In another embodiment of the invention, the hydrocarbon feed mixture is contacted with the adsorbent in the liquid phase. The temperature and pressure should be correlated accordingly. In general, the adsorption is usually carried out at a temperature between about 0° F. and about 800° F. and at a pressure between about 0 p.s.i.g. and about 1,000 p.s.i.g., preferably at a temperature between about 50° F. and about 300° F. and at a pressure between about 0 p.s.i.g. and 200 p.s.i.g. The immediate products of the initial adsorption step are (1) a liquid non-adsorbed phase which is rich in the naphthenic components of the feed mixture and lean in the non-naphthenic components, e.g., paraffins and aromatics, and (2) a solid rich adsorbent containing adsorbed non-naphthenic compounds and lean in naphthenes. The solid and liquid phases are separated, and the latter is passed to storage as the purified naphthene product of the process. The rich adsorbent, on the other hand, is treated to desorb the non-naphthenic hydrocarbons therefrom and to return it to a lean state for re-use. In accordance with one mode of operation, such treatment merely comprises subjecting the rich adsorbent to an elevated temperature and/or reduced pressure. For example, when the initial adsorption step is carried out at 200° F. under 100 p.s.i.g., the adsorbed components can be effectively recovered by heating the rich adsorbent to 600° F. and/or reducing the pressure to 0 p.s.i.g. or less. The use of elevated temperatures and/or reduced pressures may also be combined with the use of a stripping fluid in the known manner.

In accordance with a preferred mode of operation, the rich adsorbent is treated with a suitable displacement exchange fluid at approximately the same temperature as that employed in the initial adsorption stage. The displacement exchange fluid can be any material which is inert with respect to the adsorbent and the feed mixture, which is adsorbable by the adsorbent, and which is readily separated from the components of the feed mixture by distillation, absorption, or other conventional means. Preferably, the displacement exchange fluid is one which has a boiling point substantially outside the boiling range of the feed mixture and has an adsorbability substantially the same as that of the adsorbed components of the feed mixture. Preferred displacement exchange fluids are ammonia and paraffin hydrocarbons boiling sufficiently below the feed mixture, i.e., containing no more than 5 carbon atoms, so as to make them easily separable from both the adsorbed and non-adsorbed phases by distillation, e.g., iso-pentane, n-pentane, iso-butane, n-butane, and the like. Other materials which can be employed include the n-olefins, iso-olefins, 1-chloro-alkanes, 1-bromo-alkanes, 1-fluoro-alkanes, alpha-omega-dihalo-alkanes, n-alkyl amines, di-n-alkyl amines, di-n-alkyl sulfides, di-n-alkyl oxides, and the like.

The following experimental examples, I to XIII, in which percentages are by volume, specifically illustrate the practice of the invention in the vapor phase.

EXAMPLE I

A naphthenic gasoline is fractionated to separate a cut boiling in the range of 165° F.-185° F. Forty volumes of this cut, consisting of 82 percent naphthenes, 15 percent iso-paraffins, and 3 percent benzene, is passed through a lean adsorbent bed of "Molecular Sieves 10X" (zeolitic calcium sodium alumino silicate) at a temperature of about 392° F. and atmospheric pressure. The effluent is collected in a series of small portions or cuts, each containing about 3 volumes. All of the feed is added by the time the third cut is collected. Steam is then passed through the bed in the same flow direction while collecting effluent cuts 4 to 13. The steam stripping is carried out without changing the temperature or pressure. Table 1 gives the composition of effluent cuts 1 to 13 illustrating the separation obtained.

Table 1

12	2.8	49	51	-----
13	2.5	31	69	-----

EXAMPLE II

A feed mixture comprising 71 percent naphthenes, 19 percent normal paraffins, and 10 percent benzene is passed over a lean adsorbent bed of "Molecular Sieves 10X" at about 392° F. and one atmosphere pressure. Forty volumes of the feed (boiling range 161° F.-165° F.) is introduced to the bed during the first three effluent cuts, then steam stripping in the same flow direction as feed flow is begun and cuts 4 to 14 are taken. Table 2 illustrates the selective vapor phase adsorption of the normal paraffins and benzene which produces an essentially pure naphthene (cyclohexane and methylcyclopentane) effluent stream.

EXAMPLE III

An aviation gasoline fraction boiling between 161° F. and 185° F. is contacted with a lean adsorbent bed of "Molecular Sieves 10X" at a temperature of about 392° F. and atmospheric pressure as in Example II. All of the forty volumes of the gasoline feed had been added by the time effluent cut 3 was taken. Steam stripping in the same flow direction as the feed flow was then begun and cuts 4 to 12 were taken. Table 3 gives the analysis of the feed and effluent cuts illustrating the separation obtained.

EXAMPLE IV

In an experiment conducted in the same manner and with the same feed as Example I, except that silica gel is substituted for the "Molecular Sieves 10X" adsorbent bed, the composition of the effluent cuts is essentially the same as that of the naphthenic feed mixture. Thus, no separation of the components occurs. Repetition of the experiment at 100° F., again yields an effluent with substantially the same paraffin-naphthene ratio as exists in the feed mixture.

EXAMPLE V

Another experiment, conducted in the same manner and with the same feed as Example III, except activated carbon is substituted for the "Molecular Sieves 10X" adsorbent bed, yields effluent cuts having essentially the same paraffin-naphthene ratio as the feed fraction. This same experiment, repeated at a temperature of about 100° F., also shows essentially no separation of the naphthenic and paraffinic hydrocarbons from each other.

EXAMPLE VI

Another run, conducted in the same manner and with the same feed as Example III with the exception that the temperature of contacting and stripping is lowered from about 392° F. to about 225° F., yields an essentially pure naphthene effluent through cut 8, and cuts 9 to 12 have compositions similar to those cuts in Example III, as shown in Table 3.

EXAMPLE VII

This run, conducted in the same manner and with the same feed as Example II except that a pressure of 100 p.s.i.g. is maintained during adsorption and stripping, yields substantially the same naphthalene-paraffin separation as shown in Table 2.

EXAMPLE VIII

In another run, a Type X strontium sodium alumino silicate is substituted for the "Molecular Sieves 10X" (calcium sodium alumino silicate) in an experiment conducted in the same manner and with the same feed as Example III. The naphthalenes are separated from the paraffins and benzene in substantially the same manner as shown in Table 3.

EXAMPLE IX

A five volume hydrocarbon mixture comprising 42 percent 2,4-dimethylpentane and 58 percent cyclohexane is circulated for a period of 60 minutes through a lean "Molecular Sieves 10X" adsorbent bed at about 392° F. and one atmosphere pressure. The unadsorbed phase contains 38 percent 2,4-dimethylpentane. The rich adsorbent is then stripped with steam at 392° F. and atmospheric pressure, yielding 1.5 volumes of hydrocarbon adsorbate which contains 50 percent cyclohexane.

EXAMPLE X

Another run, conducted in the same manner and with the same feed as Example IX, except that ammonia is used for stripping, yields a hydrocarbon adsorbate of substantially the same amount and composition as found in Example IX.

EXAMPLE XI

This run, conducted in the same manner and with the same feed as Example IX except that iso-pentane is used for stripping, yields a hydrocarbon adsorbate of substantially the same amount and composition as found in Example IX.

EXAMPLE XII

A five volume hydrocarbon mixture comprising 49 percent cyclopentane and 51 percent 2,2-dimethylbutane is circulated for a period of 60 minutes through a lean "Molecular Sieves 10X" adsorbent bed at about 392° F. and one atmosphere pressure. The unadsorbed phase, lean in 2,2-dimethylbutane, contains 54 percent cyclopentane. The rich adsorbent is steam stripped at 392° F. and one atmosphere producing 1.2 volumes of a hydrocarbon adsorbate which contains 61 percent 2,2-dimethylbutane.

EXAMPLE XIII

Another five volume hydrocarbon mixture comprising 47 percent n-hexane and 53 percent methylcyclopentane is circulated for one hour through a lean "Molecular Sieves 10X" adsorbent bed at about 392° F. and one atmosphere pressure. The methylcyclopentane is less selectively adsorbed and the unadsorbed phase contains 43 percent n-hexane. A 1.8 volume adsorbed hydrocarbon phase, desorbed by steam stripping the rich adsorbent, contains 53 percent n-hexane.

The following Examples XIV to XVIII, in which percentages are by volume, specifically illustrate the practice of the invention in the liquid phase.

EXAMPLE XIV

Forty volumes of a full range aviation gasoline consisting of 41 percent paraffins, 5 percent C₆-C₈ aromatics, and 54 percent mononaphthalenes is passed in liquid phase through a lean adsorbent bed of a 20-45 mesh "Molecular Sieves 10X" (calcium sodium alumino silicate) at a temperature of about 72° F. and atmospheric pressure. The analysis of the first unadsorbed fraction or raffinate cut, amounting to ten volumes of the initial charge, has a composition of 40 percent paraffins and 60 percent naph-

thenes. The second raffinate cut of ten volumes has a composition corresponding to about 38 percent paraffins and about 62 percent naphthalenes. Thus, the ratio of naphthalenes to paraffins increases from 1.32/1.00 in the feed to 1.50/1.00 in the first cut and to 1.63/1.00 in the second cut which illustrates the highly selective adsorption of the paraffins in the liquid phase contacting of this invention.

The rich adsorbent is then liquid phase contacted with benzene without changing the temperature or pressure yielding an extract phase rich in adsorbed aromatics and paraffins.

EXAMPLE XV

In another run conducted in the same manner and with the same feed as Example XIV, except that the temperature is raised from 72° F. to 200° F. and the pressure is raised from atmospheric to 100 p.s.i.g., the composition of the raffinate cuts is essentially the same as that found in Example XIV and a corresponding substantial paraffin enrichment of the extract phase is also observed.

EXAMPLE XVI

In an experiment conducted in the same manner and with the same feed as Example XIV, except that activated carbon is substituted for the "Molecular Sieves 10X" adsorbent bed, the raffinate naphthalene-paraffin ratio is essentially the same as that of the naphthalene feed mixture. Thus, there is no separation of these components.

EXAMPLE XVII

Another experiment conducted in the same manner and with the same feed as Example XIV, except that silica gel is substituted for the "Molecular Sieves 10X" adsorbent bed, yields a raffinate having essentially the same naphthalene-paraffin ratio as the feed fraction. Again, there is no selectivity shown on silica gel between the naphthalene and paraffin hydrocarbons.

EXAMPLE XVIII

In this run, the unadsorbed or raffinate phase of Example XIV is reprocessed in the same manner as the original feed and a correspondingly higher naphthalene concentration is obtained in the resulting raffinate phase. The final naphthalene concentration is about 95 percent after nine successive stages of treatment.

The present class of adsorbents has relatively strong adsorptive affinity toward highly polar compounds, e.g., ethers, thioethers, water, alcohol, mercaptans, heterocyclic nitrogen or sulfur compounds, etc. The presence of such compounds in the feed stream may more or less interfere with the adsorption process of the invention, and preferably they should accordingly be removed prior to contacting the feed with the adsorbent. Such removal can be effected in various ways, e.g., by contacting the feed with an inorganic halide such as copper chloride, calcium chloride, magnesium chloride or the like, or with a suitable partially dehydrated metallo alumino silicate.

Although the deactivation of the adsorbent is gradual, some deactivation can eventually occur. It is within the scope of this invention to reactivate the silicate adsorbent in any conventional manner, e.g., by high temperature contacting with a hot reactivating gas such as flue gas, air, etc.

As will be apparent, the process of the invention essentially comprises solids-fluid contacting operations, and any of the various techniques and equipment conventionally applied to such type of operation can be adapted to the practice of the invention without departing from the scope thereof. Thus, while it is often preferred to maintain the adsorbent in the form of a moving bed, i.e., as a solids-fluid contacting operation in which a compact bed of the adsorbent is passed successively through adsorption and desorption zones where it is concurrently or countercurrently contacted with the feed stream and the displacement exchange fluid, respectively, the process

is, nevertheless, operable in the form of a fixed compact bed. Also, the solids-fluid contacting operation can be carried out employing fluidized techniques whereby the adsorbent is employed in relatively small particle size and is suspended by the flow of the fluid with which it is contacted. Other adaptable techniques and modification will be apparent to those skilled in the art.

In the foregoing specification and in the appended claims, the material to which the process of the invention is applied is described as a hydrocarbon mixture comprising certain hydrocarbon components. It is to be understood, however, that the term is meant to include mixtures of hydrocarbons containing small normally incident amounts of nitrogen, sulfur, and oxygen components.

This application is a continuation-in-part of our prior co-pending applications Serial No. 746,601, filed July 7, 1958, now abandoned, and Serial No. 775,734, filed November 24, 1958, now abandoned.

Other modifications and adaptations which would occur to one skilled in this particular art are to be included in the spirit and scope of this invention as defined by the following claims.

We claim:

1. A process for separating a fluid hydrocarbon mixture comprising naphthenic and non-naphthenic hydrocarbons which comprises: contacting said hydrocarbon mixture with a solid granular adsorbent comprising a partially dehydrated crystalline zeolitic metalloc alumino silicate having pores of substantially uniform diameter between about 7 Å. and about 12 Å. whereby there is obtained a rich adsorbent containing adsorbed hydrocarbons and an unadsorbed fluid raffinate product; and separating said rich adsorbent from said unadsorbed liquid raffinate product, said unadsorbed liquid raffinate product being substantially leaner in non-naphthenic hydrocarbons than said hydrocarbon mixture.

2. A process as defined in claim 1 wherein said adsorbent has a pore diameter of about 10 Å.

3. A process as defined in claim 1 wherein said rich adsorbent is treated to remove adsorbed hydrocarbons therefrom.

4. The process for separating a hydrocarbon mixture comprising naphthenes containing from about 5 to about 6 carbon atoms and paraffins which are difficult to separate therefrom by distillation, which comprises: (1) contacting said mixture in the vapor phase with a lean granular adsorbent comprising a partially dehydrated metalloc alumino silicate having pores of substantially uniform diameter between about 7 Å. and about 12 Å., said contacting being effected at a temperature below about 800° F., whereby there is obtained a rich adsorbent containing adsorbed paraffins and a raffinate product which is rich in naphthenes; (2) separating said raffinate product from said rich adsorbent; and (3) treating said rich adsorbent to remove adsorbed paraffins therefrom.

5. A process according to claim 4 wherein the said adsorbent comprises a calcium sodium alumino silicate having substantially uniform diameter pores of about 10 Å.

6. A process as defined by claim 4 wherein, in Step (3), said rich adsorbent is contacted with a displacement exchange fluid to obtain an extract product comprising said desorbed paraffins and said displacement exchange fluid and said extract product is treated to separate said displacement exchange fluid therefrom.

7. A process for separating cyclopentane from a hydrocarbon mixture comprising cyclopentane and paraffin hydrocarbons boiling no more than 20° F. below said cyclopentane, which process comprises: (1) contacting said hydrocarbon mixture in the vapor phase with a lean granular adsorbent comprising a partially dehydrated crystalline zeolitic calcium sodium alumino silicate having substantially uniform diameter pores of about 10 Å., said contacting being effected at a temperature between

about 100° F. and about 650° F. and at a pressure between about 0 p.s.i.g. and about 200 p.s.i.g., whereby there is obtained a rich adsorbent containing adsorbed paraffin components of said mixture and a raffinate product which is rich in cyclopentane; (2) separating said raffinate product from said rich adsorbent; and (3) treating said rich adsorbent to desorb the adsorbed paraffin therefrom.

8. A process as defined by claim 7 wherein, in Step (3), said rich adsorbent is contacted with a displacement exchange fluid to obtain an extract product comprising said desorbed paraffins and said displacement exchange fluid and said extract product is treated to separate said displacement exchange fluid therefrom.

9. A process for separating naphthenes containing 6 carbon atoms from a hydrocarbon mixture comprising said naphthenes and paraffin hydrocarbons boiling no more than 20° F. below said naphthenes, which process comprises: (1) contacting said mixture in the vapor phase with a lean granular adsorbent comprising a partially dehydrated crystalline zeolitic calcium sodium alumino silicate having substantially uniform diameter pores of about 10 Å., said contacting being effected at a temperature between about 100° F. and about 650° F. and at a pressure between about 0 p.s.i.g. and about 200 p.s.i.g., whereby there is obtained a rich adsorbent containing adsorbed paraffin components of said mixture and a raffinate product which is rich in said naphthenes; (2) separating said raffinate product from said rich adsorbent; and (3) treating said rich adsorbent to desorb said adsorbed paraffins therefrom.

10. A process as defined by claim 9 wherein, in Step (3), said rich adsorbent is contacted with a displacement exchange fluid to obtain an extract product comprising said desorbed paraffins and said displacement exchange fluid and said extract product is treated to separate said displacement exchange fluid therefrom.

11. A process for the separation of cyclohexane from a saturated hydrocarbon fraction boiling in the range from about 75° C. to about 85° C. which comprises passing the fraction through a mass of Type X synthetic zeolite of about 10 Å. units pore diameter, recovering as effluent a stream enriched in cyclohexane relative to the fraction charged, discontinuing passage of additional mixture to the sorbent mass after an amount has been charged which is sufficient to substantially reduce the capacity of the sorbent to resolve additional portions of said mixture, and thereafter desorbing the remaining hydrocarbons from said sorbent mass.

12. The process for upgrading a wide boiling range hydrocarbon mixture comprising naphthenic and non-naphthenic hydrocarbons boiling within the gasoline boiling range, which comprises: contacting said hydrocarbon mixture in liquid phase with a solid granular adsorbent essentially comprising a partially dehydrated crystalline zeolitic metalloc alumino silicate having pores of substantially uniform diameter between about 7 Å. and about 12 Å. whereby there is obtained a rich solid adsorbent containing adsorbed hydrocarbons and an unadsorbed liquid raffinate product; and separating the rich solid adsorbent from the unadsorbed liquid raffinate product, said unadsorbed liquid raffinate product being substantially richer in naphthenic hydrocarbons than said hydrocarbon mixture.

13. The process for upgrading a hydrocarbon mixture comprising naphthenic and non-naphthenic hydrocarbons boiling within the gasoline boiling range, which comprises: (1) contacting said hydrocarbon mixture in the liquid phase with a solid granular lean adsorbent essentially comprising a partially dehydrated crystalline zeolitic metalloc alumino silicate having pores of substantially uniform diameter between about 7 Å. and about 12 Å., said contacting being effected at a temperature below about 800° F. whereby there is obtained a rich adsorbent containing adsorbed non-naphthenic hydrocarbon com-

ponents of said mixture and a raffinate product which is rich in the naphthenic hydrocarbon components of said mixture; (2) separating said raffinate product from said rich adsorbent; (3) treating said rich adsorbent to desorb said adsorbed non-naphthenic hydrocarbons therefrom.

14. A process as defined by claim 13 wherein said adsorbent comprises a partially dehydrated crystalline calcium sodium alumino silicate having substantially uniform pores of about 10 Å. in diameter.

15. The process for treating a wide boiling range hydrocarbon mixture of the gasoline boiling range comprising naphthenic and non-naphthenic hydrocarbons, which process comprises: (1) contacting said hydrocarbon mixture in the liquid phase with a solid granular lean adsorbent essentially comprising a partially dehydrated crystalline metallo alumino silicate having pores of substantially uniform diameter between about 7 Å. and about 12 Å., said contacting being effected at a temperature between about 50° F. and about 300° F. and a pressure between about 0 p.s.i.g. and about 200 p.s.i.g. whereby there is obtained a rich adsorbent containing adsorbed non-naphthenic hydrocarbons and a raffinate product which is rich in naphthenes; (2) separating said raffinate product from said rich adsorbent; and (3) treating said rich adsorbent to recover said adsorbed non-naphthenic hydrocarbons therefrom.

16. A process according to claim 15 wherein the metal of said metallo alumino silicate adsorbent is predominantly a divalent metal.

17. A process according to claim 15 wherein the metal of said metallo alumino silicate adsorbent is predominantly calcium and wherein the pore diameter of said adsorbent is about 10 Å.

18. A process as defined by claim 15 wherein, in Step (3), said rich adsorbent is contacted with a displacement exchange fluid to obtain an extract product comprising said desorbed non-naphthenic hydrocarbons and said displacement exchange fluid and said extract product is treated to separate said displacement exchange fluid therefrom.

19. A process according to claim 15 wherein said mixture has an initial boiling point not less than about 100° F. and a final boiling point not greater than about 400° F.

20. The process for separating a wide boiling range hydrocarbon mixture comprising naphthenic and non-naphthenic hydrocarbons, said mixture boiling between about 100° F. and about 400° F., which comprises: (1) contacting said mixture in the liquid phase with a solid granular lean adsorbent essentially comprising a partially dehydrated crystalline zeolitic calcium sodium alumino silicate having substantially uniform pores of about 10 Å. in diameter, said contacting being effected at a temperature between about 50° F. and about 300° F. and a pressure between about 0 p.s.i.g. and about 200 p.s.i.g., whereby there is obtained a rich adsorbent having non-naphthenic hydrocarbons adsorbed thereon and a raffinate product which is rich in naphthenes; (2) separating said raffinate product from said rich adsorbent; (3) contacting said rich adsorbent with a displacement exchange fluid comprising a paraffin hydrocarbon which is readily separable from the components of said mixture, said contacting being effected at a temperature between about 50° F. and about 300° F. and a pressure between about 0 p.s.i.g. and about 200 p.s.i.g., whereby there is obtained an extract product rich in said non-naphthenic hydrocarbons and a lean adsorbent; (4) separating said extract product from said lean adsorbent; (5) returning said lean adsorbent to Step (1); (6) separately treating said extract and raffinate products to separate said displacement exchange fluid therefrom; and (7) returning said separated displacement exchange fluid to Step (3).
